[57] CLAIM

The ornamental design of a sharps container, as shown and described.

DESCRIPTION

FIG. 1 is a front elevational view of a sharps container showing my new design;

FIG. 2 is a top plan view thereof;

FIG. 3 is a side elevational view thereof, the opposite side elevational view being a mirror image of that shown;

FIG. 4 is a rear elevational view thereof;

FIG. 5 is a bottom plan view thereof; and,

FIG. 6 is a side elevational view thereof with its lid in open condition.

*Fig. 2.**Fig. 1.**Fig. 3.**Fig. 4.**Fig. 6.**Fig. 5.*
